United States Patent Office

Des. 196,382
Patented Sept. 24, 1963

196,382

LIGHT DIFFUSER PANEL

Robert A. D. Schwartz, % Athens Athletic Club,
1215 Clay St., Oakland, Calif.

Filed Mar. 30, 1961, Ser. No. 64,543

Term of patent 14 years

(Cl. D48—16)

FIG. 1.

FIG. 2.

FIG. 3.

FIG. 4.

I claim:

The ornamental design for a light diffuser panel, substantially as shown.
